UNITED STATES PATENT OFFICE.

GEORGE H. KLOBUCHAR, OF RATHBUN, IOWA.

LOCK.

1,100,579.

Specification of Letters Patent. Patented June 16, 1914.

Application filed March 30, 1914. Serial No. 828,311.

To all whom it may concern:

Be it known that I, GEORGE H. KLOBUCHAR, a citizen of the United States, residing at Rathbun, in the county of Appanoose and 5 State of Iowa, have invented certain new and useful Improvements in Locks, of which the following is a specification.

This invention has for its object to provide a lock of novel construction which can 10 be operated only by a special form of key, and also to provide a lock which is strong and durable and devoid of complicated parts liable to get out of order. These objects are attained by means of a combination and arrangement of parts to be hereinafter described and claimed, reference being had to the accompanying drawing, in which—

Figure 1 is a front elevation of the lock, partly broken away; Fig. 2 is a face view of 20 the lock with a portion of the casing removed; Fig. 3 is a cross-section on the line 3—3 of Fig. 2, and Fig. 4 is a cross-section on the line 4—4 of Fig. 3.

Referring specifically to the drawing the 25 casing of the lock comprises two plates 5 and 6, respectively, placed face to face, and secured together by screws or other suitable fasteners 7. In the contiguous or inner faces of the plates are matching grooves 8 forming a seat for a sliding bolt 9, said seat 30 opening through one end of the casing so that the bolt may be projected therefrom to enter its keeper. In the contiguous faces of the plates are also two matching grooves 10 35 extending at right angles to the bolt seat and opening thereinto, which grooves form guide-ways for sliding tumblers 11 adapted to enter notches 12 in the side of the bolt for the purpose of locking the same when it is 40 advanced into its keeper. The tumblers are spring-pressed, small coiled springs 13 being mounted in the guide-ways behind the tumblers to press the same forward into locking position.

45 In the plate 5 is a key-hole 14 and in the inner face of said plate, between the guide-ways 10 is a recess 15 which is intersected by the key-hole. This recess is stepped or of different depths on opposite sides of the key-hole. In the sides of the tumblers 11 which face each other are notches 16 adapted to be entered by the bits of the key to be presently described. These notches are flush with the respective sides of the recess 15. In the 50 inner face of the plate 6, between the guide-ways 10, is a recess 17 to accommodate one

of the key bits. The bolt 9 has a stem 18 which extends through a slot 19 in the plate 5 and has on the outside of the latter a knob 20, whereby the bolt may be advanced 60 or retracted when unlocked.

A compound key is provided for the herein described lock. The key has a tubular shank 21 on one end of which is a laterally extending finger-piece 22, and on the other end of the shank is a bit 23 in the form of a laterally projecting finger. Intermediate its ends, the shank has a shoulder 24 to limit the extent to which the key may be inserted into the key-hole 14. In the hollow of the 70 shank 21 is rotatably mounted a shank 25 having a finger-piece 26 at one end and a bit 27 at the other end. The bit 27 is in advance of the bit 23.

In operation, the finger-pieces 22 and 26 75 are brought together, which places the bits 23 and 27 in parallel position, one behind the other. The key may now be inserted into the key-hole 14, and after it has entered the same as far as the shoulder 24 80 permits, the bits are spread or swung in opposite directions in the recess 15 by spreading the finger-pieces 22 and 26. One of the bits enters the notch 16 of one of the tumblers 11 and the other bit enters the 85 notch of the other tumbler. Now, upon continuing to spread the finger-pieces, the bits retract the tumblers, and when the latter clear the notches 12 of the bolt 9, the bolt may be retracted. When the bolt is advanced to locking position, the springs 13 90 shoot the tumblers 11 forward into the bolt notches upon the latter coming in line with the tumblers. That side of the recess 15 in which the bit 23 works is deeper than 95 the side in which the bit 27 works, and the recess 17 matches with the last-mentioned side.

The lock is simple, strong and durable, and it can be made right or left handed. 100

I claim:

1. A lock comprising a casing having a key-hole, a bolt and sliding tumblers in the casing, the tumblers working transversely of the bolt on the same side thereof 105 and the latter having notches to receive the tumblers, the key-hole of the casing being located between the tumblers, and a key comprising a tubular shank having a bit at one end, and a shank rotatably mounted in said tubular shank and having a bit at 110 one end adjacent to the first-mentioned bit,

said bits being insertible through the key-hole to come between the tumblers and adapted to be spread to engage the respective tumblers to retract the same.

5 2. A lock comprising a casing having a key-hole, a bolt and sliding tumblers in the casing, the tumblers working transversely of the bolt on the same side thereof and the latter having notches to receive the tumblers, the key-hole of the casing being located between the tumblers, and a key comprising a pair of rotatably connected shanks having each a bit at one end, said bits being insertible through the key-hole to 10 come between the tumblers and adapted to be spread to engage the respective tumblers to retract the same.

15 3. A lock comprising a casing having a key-hole, a sliding bolt and tumblers in the casing, the tumblers working transversely

of the bolt and the latter having notches to receive the tumblers, the key-hole of the casing being located between the tumblers, and the wall of the casing having a recess 25 into which the key-hole opens, the tumblers having side notches which are opposite each other and in line with the aforesaid recess, and a key comprising a pair of rotatably connected shanks having each a bit at one end, said bits being insertible through the 30 key-hole to enter the recess between the tumblers, and adapted to be spread in said recess to enter the tumbler notches and retract the tumblers.

In testimony whereof I affix my signature in presence of two witnesses.

GEORGE H. KLOBUCHAR.
